(57) **CLAIM**

The ornamental design for a cross-shaped calendar, as shown and described.

DESCRIPTION

FIG. 1 is a front perspective view of a cross-shaped calendar in accordance with the present invention;

FIG. 2 is a rear perspective view thereof;

FIG. 3 is a front thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 6 Drawing Sheets
